BRAKE SHOE TURNING MACHINE

Stanley Whitworth and Leland E. Long, South Bend, Ind., assignors to Bendix Brake Company, South Bend, Ind., a corporation of Illinois

Application November 8, 1930. Serial No. 494,352

5 Claims. (Cl. 82—2)

This invention relates to machines for turning or otherwise operating on brake shoes or the like, and is illustrated as embodied in a turret type of machine having a series of cutting tools. 5 Various features of the invention relate to the construction of the turret to hold the shoes, to the operation of the cutting tools, to a novel device for feeding shoes to the turret or its equivalent, to an ejecting means for the turned shoes, 10 and to the arrangement of these various elements in an organized machine arranged to be readily controlled by the operator.

The above and other objects and features of the invention, including various novel and desirable details of construction, will be apparent 15 from the following description of the illustrative embodiment shown in the accompanying drawings, in which:

Figure 1 is a perspective view of the machine; 20 Figure 2 is a perspective view of the turret and feeding means, with the latter in a different position from Figure 1;

Figure 3 is a vertical section through the 25 turret;

Figure 4 is a section through the shoe-holding means at the end of one of the arms of the feeding means; and

Figure 5 is a detail perspective view of part 30 of the turret, showing the mounting of one of the leaf springs used to eject the turned shoes.

The illustrated machine includes a suitable hollow table or supporting frame 10 having a door 12 affording access to the parts mounted in the interior, and on the top of which is 35 mounted a stationary support in the form of a transverse arm 14.

At the center of the machine is a turret, indicated generally at 16, and which includes a base 18 rotatably mounted on suitable bearings 40 on the table 10 and formed with an internal gear 20 driven by a pinion 22 operated by a suitable electric motor mounted in any desired manner inside of the table 10.

Bolted or otherwise secured to the base 18 45 is a circular lower section 24, to which is secured a driving column 26 on which are keyed a series of intermediate circular sections 28 and an upper section 30. The sections 24—28—30 are arranged to grip between them the webs of 50 brake shoes or the like, with the rims of the shoes supported by the periphery of the sections as shown in Figure 3. The edges of the sections are beveled as shown in Figure 3, to facilitate inserting the shoe webs between them.

55 The sections are urged apart, to permit the

insertion or removal of the shoes, by means such as springs 32 confined between the lower faces of the movable sections 28 and the upper faces of stops 34 secured to the column 26. Stops 34 may be made in two semicircular pieces set 60 into grooves in the column 26 and fastened together by screws or the like.

Springs 32 urge the sections 28 upwardly against the stops, thereby releasing the shoe webs, and the shoes are thereupon ejected by means such as leaf 65 springs 36 fastened at their centers in the bottoms of peripheral grooves 38 in sections 28 and having their ends engaging the rims of the shoes. The insertion of the shoes when loading the turret depresses the springs 36 into their grooves 38. 70

The upper section 30 is fastened to a sleeve 40 sliding on the column 26 inside of a bearing 42 carried by the supporting arm 14. Sleeve 40 in turn is fastened to the base 44 of a double-ended movable air cylinder 46, within which is a suitable piston (not shown) having a stationary piston rod 48 fastened to the top of the column 26. 75

Compressed air is supplied to the movable cylinder 46, above or below its stationary piston, through a suitable fitting 50 mounted on the upper end of the stationary piston rod 48, by means of conduits such as pipes 52, under the control of valves operated by two pedals 54. One of the 80 pedals 54 causes the cylinder 46, with the section 30, to be raised to release and eject the shoes, 85 while the other pedal causes the cylinder 46, with section 30, to be forced downwardly to grip the shoes while they are being turned.

Shoes mounted on the turret while it is rotating are operated on by means such as a series of cutters 56 adjustably clamped on a slide 58 raised and lowered by a screw 60 operated by a motor 62. The slide 58 is dovetailed onto a support 64 which also carries the motor, and which at its bottom is dovetailed onto the top of table 10 so that it may be 95 adjusted toward and from the turret by manipulating a handwheel 66.

The circuit of motor 62 includes a switch 68 on the slide 58, arranged to engage a stop 70 when the slide is in its lowermost position and a stop 100 72 when the slide is in its uppermost position, and in either case to interrupt the circuit so that the slide cannot be moved again until the direction of the motor is reversed.

The circuits of both motors, i. e., motor 62 and 105 the motor for the turret, are broken or completed not only by the automatic switch 68 which stops the machine automatically when one load of shoes has been turned, but also by a manually-operated switch 74. Switch 74 has three positions, 110

one extreme position in which the motor 62 is turning in one direction and in the other of which this motor is reversed, and in both of which positions the turret motor is driven in the same direction, together with an intermediate switch position in which both motor circuits are broken and the machine stopped.

The shoes are fed to the turret, after ejection of the shoes previously turned and while the turret sections are separated, by apparatus shown as including a pair of arms 80 pivoted at opposite ends of a shaft 82 journaled in the supporting arm 14 in such a manner as to turn with the shaft while yet being capable of movement toward and from each other.

Each arm 80 has rockably mounted thereon a head 84 (Figure 4), provided with means such as pairs of leaf springs 86 arranged yieldingly to grip the shoes by the rims with the webs presented outwardly, as the operator inserts them when the arms 80 are in the position of Figure 1. A suitable counterweight 88 is linked to the rear end of one arm 80, so that the arms are practically balanced when carrying a full load of eight shoes, whereby the operator can readily swing the feeding apparatus to the position of Figure 2, with his left hand.

Between the rear ends of the arms 80 is arranged a compressed air cylinder and piston assembly 90, the piston being connected to one arm and the cylinder to the other. Air is supplied by flexible hose conduits 92, under the control of a suitable valve 94 arranged to be controlled by the operator's right hand.

Assuming the machine in the position of Figure 1, with a load of shoes just turned, the operator having loaded the arms 80, the operator now steps on the proper pedal 54, whereupon the air moves the cylinder 46 and the sections 28 upwardly, releasing the turned shoes, which are thereupon ejected by the springs 36.

The operator next swings the arms 80, with his left hand, to the position of Figure 2, and then manipulates valve 94 with his right hand to cause the arms 80 to swing toward each other to insert the webs of the unturned shoes between the sections 28. The other pedal 54 is next depressed to move the cylinder 46 downwardly, to clamp the webs of the unturned shoes firmly in the turret.

The operator's right hand then operates valve 94 to move the arms 80 away from each other, whereupon weight 88 swings them back to the position of Figure 1. The switch 74 is next swung to its opposite extreme position, whereupon the turret begins to turn, and at the same time the slide 58 begins to move slowly upwardly (or downwardly, as the case may be). The operator then

proceeds to load the arms 80 with more unturned shoes, while the machine is turning the ones on the turret.

While one illustrative embodiment has been described in detail, it is not our intention to limit the scope of the invention to that particular embodiment, or otherwise than by the terms of the appended claims.

We claim:

1. A machine for turning brake shoes or the like comprising a rotatable turret arranged to support a plurality of shoes on each side by gripping their webs and leaving their rims substantially unobstructed, a tool having cutters for operating on the rims of said shoes, and a feeding device for mechanically supplying unturned shoes to said turret.

2. A machine for turning brake shoes or the like comprising a rotatable turret arranged to support a plurality of shoes on each side by gripping their webs and leaving their rims substantially unobstructed, and a feeding device for mechanically supplying unturned shoes to said turret.

3. A machine for turning brake shoes and the like comprising a turret and a motor for driving it, in combination with an adjustable support having a reversible motor mounted thereon and provided with a slide carrying cutting means arranged to operate on work carried by the turret and driven by said motor in both directions, together with a controlling device having two positions, one arranged to cause the reversible motor to drive the slide in one direction and the other to cause it to drive the slide in the other direction and both arranged to cause the first motor to drive the turret in the same direction.

4. A machine comprising a turret constructed and arranged to hold brake shoes or the like by the webs with their rims substantially unobstructed, in combination with feeding means constructed and arranged to hold such shoes by the rims with the webs unobstructed and to present them in position for the gripping of said webs by the turret.

5. A machine comprising a turret constructed and arranged to hold brake shoes or the like by the webs with their rims substantially unobstructed, in combination with feeding means constructed and arranged to hold such shoes by the rims with the webs unobstructed and to present them in position for the gripping of said webs by the turret, and power means for moving the feeding means to present the shoes in said position.

CERTIFICATE OF CORRECTION.

Patent No. 1,940,474.

December 19, 1933.

STANLEY WHITWORTH, ET AL.

It is hereby certified that error appears in the printed specification of the above numbered Patent requiring correction as follows: Page 2, second column, after line 129, insert the following as claim 6;

6. A machine comprising a turret constructed and arranged to hold brake shoes or the like by the webs with their rims substantially unobstructed, in combination with feeding means constructed and arranged to hold such shoes by the rims with the webs unobstructed and to present them in position for the gripping of said webs by the turret, and cutting means for operating on the rims of shoes carried by the turret.;

and that the said Letters Patent should be read with this correction therein that the same may conform to the record of the case in the Patent Office.

Signed and sealed this 19th day of March, A. D. 1935.

(Seal)

Leslie Frazer
Acting Commissioner of Patents.
